UNITED STATES PATENT OFFICE.

GRANVILLE H. STALLMAN, OF CINCINNATI, OHIO, ASSIGNOR TO THE C. SCHMIDT COMPANY, OF CINCINNATI, OHIO, A CORPORATION OF OHIO.

HOG-SCRAPER.

1,101,154.

Specification of Letters Patent. Patented June 23, 1914.

Application filed June 10, 1912. Serial No. 702,769.

To all whom it may concern:

Be it known that I, GRANVILLE H. STALLMAN, a citizen of the United States, residing at Cincinnati, in the county of Hamilton and State of Ohio, have invented certain new and useful Improvements in Hog-Scrapers, of which the following is a specification.

My invention relates to improvements in hog scraping and cleaning mechanism.

One of its objects is to provide mechanism whereby the hogs are regularly and automatically fed through the mechanism and uniformly subjected to the scraping and cleaning mechanism.

Another object is to provide improved scraping and cleaning mechanism capable of reaching and uniformly treating all parts of the body.

Another object is to provide improved mechanism to support and rotate the body during the scraping and cleaning operation.

Another object is to provide improved means to automatically discharge the body after the scraping and cleaning operation is completed, and to resume position to receive another hog.

Another object is to provide improved scraping and cleaning mechanism.

My invention further comprises certain details of form, combination and arrangement, all of which will be fully set forth in the description of the accompanying drawings in which:

Figure 1 is a side elevation of my improved mechanism. Fig. 2 is an enlarged detail of one form of sprocket chain employed. Fig. 3 is a top plan view. Fig. 4 is an enlarged sectional detail on line $x-x$ of Fig. 3. Fig. 5 is a similar view on line $v-v$ of Fig. 3. Fig. 6 is a sectional detail through one of the revolving scrapers, illustrating a modification.

The accompanying drawings illustrate the preferred embodiment of my invention in which A represents a structural iron frame into which is preferably built a tank A' to hold water for use during the scraping and cleaning operation. Mounted upon the frame A is a cast frame B provided with journal bearings to support the operative mechanism.

C represents a scalding vat in which the hogs are scalded before passing to the scraping mechanism. The hogs are lifted one at

a time from the scalding vat by means of a series of hooks 2 carried by sprocket chains 3 which are supported upon sprocket wheels 4 carried by shaft 5 at one end and upon sprocket wheels 6 carried by shaft 7 at the other end. The shaft 5 is journaled in boxes 8 below the surface of the water in the scalding vat carried by standards 9 from the floor of the vat. The shaft 7 is journaled in boxes 10 carried by the standards 11 of frame A. A series of angle irons 12 strung upon cross rod 13 form an inclined guideway down which the body of the hog may roll after it has been elevated by the hooks 2 to a position above the shaft 7. In order that the hog may roll instead of slide down the inclined bars 12, the upper edges of said bars are provided with notches 14. The outside bars 12 are bolted to the frame while the intermediate bars 12 rest upon the shafts 7 and 15 and upon the edge of the vat C, being held in place by the cross rod 13.

The shaft 15 is journaled at opposite ends, in the frame B and is provided with a series of sprocket wheels 16 spaced equidistant apart. Sprocket wheels 17 of the same diameter are mounted upon the shaft 18 which is also journaled to frame B and a series of sprocket chains 19 are supported upon the wheels 16 and 17. A pair of arms 20 are pivotally supported at one end upon the shaft 18 while a shaft 21 is journaled in bearings 22 at the opposite or free ends of arms 20. A series of sprocket wheels 23 are mounted upon shaft 18 alternately with the sprocket wheels 17. Sprocket wheels 24 are mounted in line with the wheels 23 on the shaft 21 and sprocket chains 25 mounted upon the respective pairs of wheels 23 and 24. The arms 20 are normally held in the position illustrated in Fig. 1 by means of latch levers 26 pivoted at 27 to the frame B and engaging pins 28 projecting from the arms 20. In this position of the arms 20 the several sprocket chains 19 and 25 form a V-shaped bed, support, or cradle for the body of the hog, and when the shaft 18 is rotated by power the chains 19 and 25 serve to drive the shafts 15 and 21, and also cause the hog to rotate with said chains as a support, or cradle.

E represents a shaft journaled at opposite ends in frame B and having a series of scraping and cleaning members 29 and 30 mounted thereon. A shaft F is journaled at

opposite ends in bearings 31 on the arms 20, and is provided with a similar series of scraping and cleaning members 29 and 30. A tight pulley 32 and loose pulley 33 on shaft E outside the frame B provide for the application of power at say approximately one hundred revolutions per minute to the shaft E. A pair of sprocket wheels 34, and 35 and chain 36 serve to transmit motion from shaft E to shaft 18 at relatively less speed than shaft E. The chains 19 and 25 receive motion from shaft 18 and in turn drive the shafts 15 and 21. The shaft 7 is driven from shaft 15 by means of sprocket wheels 37 and 38 and chain 39. Loosely mounted upon the shaft 18 is a sleeve upon which are rigidly mounted two sprocket wheels 40 and 40', which are driven from shaft E by means of a chain 42 from sprocket wheel 41 on shaft E while a chain 43 driven by the wheel 40' engages a sprocket wheel 43' on shaft F and serves to drive shaft F at the same speed as shaft E, and irrespective of the position of the arms 20.

23 A shaft 44 journaled at opposite ends to frame B receives relatively slow motion from shaft 15 by means of a chain 45 running over the sprocket wheels 46 and 47. Sprocket wheels 48 on shaft 44 serve by means of sprocket chains 49 to drive at a still slower rate the sprocket wheels 50 which are mounted upon stud shafts carried by the frame 13. The wheels 50 are armed with crank pins 50' which at regular intervals engage the upwardly projecting arms 51 of the latch members 26 to trip said latch members to release the arms 20, which under the weight of the hog resting upon the chains 25 assume a substantially horizontal position 40 whereupon the chains 25 feed the hog over the sprocket wheels 24 and onto a table or conveyer 52 ready to be inspected and then carried away on the overhead track 53. Immediately, after the chains 25 and arms 20 are relieved of the weight of the hog, the counterweights 54 attached by cables 55 passing over rollers 56 on frame B cause the arms 20 to resume the position illustrated in Fig. 1, in position to receive another hog.

50 During the operation of cleaning warm water supplied by pipe 57 is sprayed upon the hog and the water, bristles and solid matter are caught upon an inclined tray 58 and conducted to a perforated trough 59 where the water is drained into tank A' and a conveyer 60 driven by a chain 61 from shaft 18 feeds the bristles or other solid matter out at one end of the trough 59. The water from tank A' may be returned to pipe 57 by means of a rotary pump 62 driven by belt 63 from pulley 64 on shaft E, or fresh water may be continuously supplied to pipe 57 and used only once and then wasted by directing it into a sewer or like receptacle.

55 In order to thoroughly scrape and clean

all parts of the hogs, I preferably provide scraping members 30 of relatively less diameter opposite the central and nearly cylindrical portion of the body and scraping members 29 of relatively greater diameter opposite the respective ends of the body. The scraping members may all be alike except as to diameter if desired, but I prefer to otherwise modify the scraping members operating upon the ends of the body as compared with those operating upon the central portion of the body. In Figs. 4 and 6, are illustrated the scraping and cleaning members preferably employed opposite the ends of the body, which comprise hubs 65 rigidly attached to the shafts E and F, said hubs having grooves 66 in which are seated strong and comparatively stiff strips 67 of canvas belting or similar material said strips being held in place upon the hubs 65 by means of clamping bars 68 bolted to the hubs. The outwardly projecting ends of the strips 67 are preferably united together and so arranged as to mutually support each other, and on the side facing the direction of rotation are provided a series of metal scrapers f formed of short sections of angle iron firmly secured to the strips 67. Two series of strips 67 are preferably secured in staggered relation to one hub, and the hubs set 95 in staggered relation upon the respective shafts E and F. The distance between the shafts E and F is such that the free ends of the strips 67 of the opposed scraping members very closely approach each other, but without liability of touching. In Fig. 1 the dotted circles 68' approximately represent the line of travel of the peripheries of scrapers 29, while the dotted circles 69 approximately represent the line of travel of the peripheries of the scrapers 30, said scrapers being otherwise omitted from Fig. 1. The strips 67 may be projected radially at right angles to the axis of the shaft as indicated in Figs. 2 and 3, or may if desired, be set diagonally with reference to the shaft axis as illustrated in Fig. 6 in which strips 67' correspond to the strips 67 of Fig. 3, being held upon the hub 70 by means of clamp members 71 and screws 72. The diagonal arrangement Fig. 6 enables the strips 67' to more readily engage and clean the tapered or rounded ends of the body. The series of scrapers f on the respective strips 67 enable both ends and also the limbs to be effectually scraped and cleaned.

The scrapers 30 comprise peripheral bands 75 of comparatively stiff but flexible canvas belting or similar material supported from the hubs 76 by means of spokes 77 composed of substantially the same material as the peripheral bands 75, to which they are united by rivets. Clamping members 78 bolted to the hubs serve to lock the spokes 77 to the hubs. A series of scrapers 79 con-

sisting of short metal angle bars are secured to the periphery of bands 75, either extending clear across the face of said bands or in shorter sections set in staggered relation.

5 Under the pressure exerted by the body of the hog, the bands 75 and spokes are free to yield or partially collapse, while the chains 19 and 25 prevent the body coming in contact with the hubs 76, hence the scrapers 79 are successively drawn with a yielding pressure across the central portion of the slowly revolving body, and serve to scrape and clean the same. In practice a body will make approximately three revolutions supported upon the chains 19 and 25 and exposed to the action of the revolving scrapers, and is then fed away to the table or conveyor 52.

The movements of the hooks 2 and the pins 50' which release the latches 26 are so timed as to automatically deliver another body onto the chains 19 and 25 as soon as the arms 20 have returned and been engaged by the latch members 26. In order to facilitate rotating the body and feeding it from the machine, I preferably provide the chains 19 and 25 with attachment lugs or teeth 80 as indicated in Fig. 2.

The mechanism herein illustrated and described is capable of considerable modification without departing from the principle of my invention.

Having described my invention, what I claim is:

35 1. A hog scraper comprising a cradle to support and rotate a hog in a substantially uniform position, and a shaft armed with yielding scraping members projecting upwardly into said cradle to engage and 40 scrape the surface of the rotating hog.

2. In a hog scraper in combination with rotary scrapers, a cradle to support and rotate the hog in position to be acted upon by said scrapers, said cradle consisting of two 45 independent conveyers traveling tandem at relatively different angles.

3. In a hog scraper in combination with rotary scrapers, a cradle to support and rotate the hog in position to be acted upon by said scrapers, said cradle comprising two conveyers traveling at relatively different angles, and means to vary the angularity of one of said conveyers to eject the hog.

4. A hog scraper comprising a cradle to support and rotate a hog in a substantially uniform position, and a shaft armed with scraping members to engage and scrape the surface of the rotating hog, said scraping members being of less peripheral diameter 55 near the central portion of the hog than at its ends.

5. A hog scraper comprising a cradle to support and rotate the hog, said cradle consisting of a series of stationarily located conveyers, and a pivotally supported and ad-

justable series of conveyers, and rotary scrapers journaled in fixed relations to said conveyers to yieldingly engage the under surface of the hog while supported in said cradle.

6. In a hog scraper in combination with rotary scrapers, a V-shaped cradle to support and rotate the hog in position to be acted upon by said scrapers, said cradle comprising two series of conveyers traveling at relatively different angles, means to automatically intermittently vary the angularity of one series of said conveyers to eject the hog, and mechanism to intermittently deliver hogs to said cradle.

7. In a hog scraper, a cradle to support and rotate the hog consisting of two series of conveyer chains traveling at relatively different angles, one of said series of chains being angularly adjustable to eject the hog, and rotary scrapers located between and in fixed relation to said chains to engage the surface of the hog while supported in said cradle.

8. In a hog scraper, a cradle to support and rotate the hog consisting of two series of conveyer chains traveling at relatively different angles, one of said series of chains being pivotally supported and adapted by changing its angular adjustment to eject the hog, and rotary scrapers located between the chains to engage the under surface of the hog while supported in said cradle.

9. A hog scraper comprising a cradle to support and rotate a hog in a substantially uniform position, a pair of shafts below and at opposite sides of said cradle armed with scraping members in staggered relation on said respective shafts, to engage and scrape the under surfaces of the rotating hog, said scraping members being of less peripheral diameter opposite the central portion of the hog than opposite its ends.

10. In a hog scraper, a cradle to support and rotate the hog consisting of two series of endless conveyers traveling at relatively different angles, and a plurality of rotary scrapers located between said conveyers to engage the surface of the hog while supported in said cradle.

11. In a hog scraper, a cradle to support and rotate the hog consisting of a stationarily located series of conveyer chains and a pivotally supported and adjustable series of conveyer chains, and rotary scrapers located between said chains to engage the under surface of the hog while supported in said cradle.

12. A hog scraper comprising a cradle to support and rotate a hog consisting of two conveyers traveling at relatively different angles, one of said conveyers being pivotally supported to eject the hogs by changing its angularity a conveyer to automatically intermittently feed hogs from a scald-

- ing vat to said cradle, means movable in synchronism with said hog feeding conveyer to eject the hogs successively from said cradle, and a series of rotary scraping members 5 to engage the surface of the hog when supported in said cradle.
13. In a hog scraper a series of inclined stationarily located conveyers, a series of pivotally supported and counter-balanced 10 conveyers in position to form with said stationarily located conveyers a cradle to support and rotate a hog, means to lock said pivotally supported conveyers in position, a shaft provided with rotary scrapers projecting 15 between said stationarily located conveyers, a shaft movable with said pivotally supported conveyers and provided with scrapers projecting between said pivotally supported conveyers, mechanism to transmit motion from one of said scraper shafts to 20 the other irrespective of the pivotal movement of one of said shafts, and means to periodically release said pivotally supported conveyers to eject the hogs.
14. In a hog scraper a series of stationarily located inclined conveyers, a pivotally supported frame carrying a series of adjustable conveyers means to lock said pivotally supported conveyers in position to form with 25 said stationarily located conveyers a cradle to support and rotate the hogs, a stationarily journaled shaft provided, with rotary scrapers projecting into said cradle between said stationary conveyers, a shaft movably 30 mounted upon said pivotally supported frame and provided with rotary scrapers projecting into said cradle between said pivotally mounted conveyers, and means to periodically release said pivotally supported frame 35 to eject the hogs.
15. In a hog scraper a V-shaped cradle to support and rotate the hogs, a pair of shafts located below said cradle and at opposite sides of the apex of said cradle, said shafts 40 being respectively provided with rotary scrapers projecting into said cradle between the conveyer sections.
16. In a hog scraper, a V-shaped cradle of traveling conveyers to support and rotate 45 the hogs, a pair of shafts located at opposite sides of the cradle and provided with rotary

scraper members projecting into said cradle, said scraper members being of less peripheral diameter opposite the central portion of the hog than at its ends. 55

17. In a hog scraper a V-shaped cradle of traveling conveyers to support and rotate the hogs, a pair of shafts at opposite sides of said cradle provided with cylindrical scraper members to act upon the central portion of the hogs and radially projecting scraper members to act upon the ends of the hogs, said scraper members projecting between the conveyer sections into said cradle. 60

18. In a hog scraper traveling conveyers 65 forming a cradle to support and rotate the hogs, and a shaft provided with yielding cylindrical scraper members to act upon the central portion of the hogs and radially projecting scraper members to act upon the ends of the hogs, said scrapers projecting into said cradle between the conveyer sections. 70

19. In a hog scraper traveling conveyers forming a cradle to support and rotate the 75 hogs, and a series of rotary scraping members rotatably supported below said cradle and projecting into said cradle between the sections of said conveyers.

20. In a hog scraper traveling conveyers 80 forming a cradle to support and rotate the hogs, and periodically adjustable to eject the hogs, and a series of rotatably mounted scraper members projecting from the under side of said conveyers between the conveyer 85 sections into said cradle.

21. In a hog scraper a V-shaped cradle of sectional traveling conveyers to support and rotate the hogs, a pair of shafts at opposite sides of said cradle each provided with a 90 series of rotary scraper members projecting into said cradle between said conveyer sections, said scraper members upon the respective shafts being in staggered relation so as to have overlapping spheres of action. 95

In testimony whereof I have affixed my signature in presence of two witnesses.

GRANVILLE H. STALLMAN.
